UNITED STATES PATENT OFFICE.

HENRY NORMAN LEASK, OF EGREMONT, ENGLAND.

CHARGING-DOORS FOR FURNACES.

1,133,978.

Specification of Letters Patent. Patented Mar. 30, 1915.

Application filed December 30, 1910. Serial No. 600,012.

To all whom it may concern:

Be it known that I, HENRY NORMAN LEASK, a British subject, residing at Egremont, county of Chester, England, have invented certain new and useful Improvements in Charging-Doors for Furnaces, of which the following is a specification.

This invention relates to improvements in doors of refuse destructor and other furnaces of the type in which the fuel is fed to the fire from the top or from a level above that of the fire and especially applicable for use in connection with furnaces having containers with bin or other receptacles arranged above the fire door into which the fuel is placed before being fed or dropped into the fire.

It consists essentially of a carriage or the like which may or may not support an upper door adapted to close the bottom of a fuel container or receptacle or means for opening and for closing doors attached to the bottom of such containers and a lower door adapted to close the actual furnace opening with or without a tundish or funnel adapted to surround the space between the container or receptacle and the furnace opening when the fuel is being fed to the fire, the furnace or lower door being connected to the upper door or carriage or its operating means by one or more links or the like and being also arranged to run on wheels upon runways or guides which immediately above the furnace opening are preferably inclined so that when the door comes over the furnace opening it is dropped down into position on or over the opening, a water, sand or other seal being provided if desired to receive a depending flange from the door adapted to enter same, said flange being preferably inclined forward so as to enter the trough in a direction parallel to the inclines in order to avoid splashing and to take up less room.

The invention will be fully described with reference to the accompanying drawings.

Figure 1 is a sectional side view showing one form of the invention with the doors closed. Fig. 2 is a similar view showing the doors open. Fig. 3 is a sectional view showing a modified arrangement. Fig. 4 is a sectional view showing another modification. Fig. 5 is a transverse section of the structure shown by Fig. 4. Fig. 6 is a sectional view of a further modified arrangement of the invention in which the up-

per carriage carries means for closing doors hinged or attached to the bottom of the container. Fig. 7 is a similar view showing a modified arrangement of structure of Fig. 6. Fig. 8 is a view showing another modified arrangement of structure of Fig. 6. Fig. 9 is a similar view showing a still further modification.

As shown in Figs. 1 and 2 a fixed hopper B is arranged over the furnace door or feed opening A and an upper carriage C running on rails c carries a plate D which is adapted normally to form a door or the like to close the bottom of the hopper B. This carriage C and plate D are arranged so that they can be reciprocated in any suitable manner as for instance by means of a hydraulic ram d. The main furnace door F for closing the feed opening is mounted upon a second carriage E which is attached to the upper carriage C or the ram d by means of a suitable link e'. The carriage E runs on suitable rails or runways e which immediately over the furnace opening are inclined upward so that when a pull is exerted upon the carriage E and door F they rise upward and a depending flange f with which it is preferably provided is lifted out of the water, sand or the like seal a arranged around the furnace opening A. This flange f is preferably inclined as above in such a manner that when the door is lowered into position the flange enters the water or sand in the seal a in a line parallel to the inclines so as to prevent or obviate any splashing.

The upper carriage C is preferably provided with a tundish or the like G which is adapted to surround the furnace opening A and to fill up the space between the bottom of the hopper B and the furnace opening so as to direct any material fed from the hopper into the fire and to prevent it entering into the seal or trough a around the opening. Where such a tundish or tunnel G is employed for directing the fuel from a container into the furnace the side g farthest from the door may be arranged separately from the tundish being for instance pivoted to the hopper B as shown and adapted to drop into position previously to the opening of the bottom of the hopper so as to prevent any fuel falling into the water or sand seal or trough a around the mouth of the furnace. A projection or the like g' upon the side g is preferably engaged by a slide g² mounted on the carriage and adapted to re-

tain the side *g* in position while the charge is passed to the fire.

It is sometimes advisable that the door *D* of the hopper *B* should not be opened till 5 the furnace door *F* is completely open. This is accomplished in the arrangement shown in Fig. 3. In this arrangement the door *F* and its carriage *E* are not directly connected to the carriage *C* but the carriage *E* is provided with a lug or projection *H* adapted 10 to engage a corresponding projection *K* on the carriage *C* to move it forward when the carriage *E* in its movement has uncovered the furnace opening *A*. The carriage *E* is 15 also provided with a second lug or projection *h* adapted to engage the trolley *C* and push it back when the doors are to be closed. The carriage *E* may be operated by a ram as 20 above described or by a chain *J* as shown or in any other suitable and convenient manner. In order to permit the flange *f* to pass the trough *a* and prevent the lug *H* from becoming disengaged from the projection *K* when the roller *g* passes into the recess of 25 the track *e*, the furnace door *F* is arranged to run upon two sets of rails so that as the furnace door is moved farther to the right than in the position shown in Fig. 2, the roller *g* will not descend into the recess of 30 the track, but keeps its level on another rail.

Another modified arrangement is shown in Figs. 4 and 5. In this arrangement instead of sealing the furnace door *F* with a water or sand seal the furnace opening *A* is 35 provided with a rim *K* the top edge of which is finished or arranged in an inclined plane. The bottom edge of the door *F* is constructed of a corresponding inclination so that when the door is moved horizontally 40 into the closing position it makes a tight joint with the rim. As shown the carriage *E* runs on separate rails *e* to the carriage *C*, but in this arrangement, if desired, both carriages may run on the same rails. The 45 bearings by which the door *F* is suspended are preferably slotted as shown so that the door *F* may be moved forward till its whole weight rests on the rim *K*.

If desired the rails *e* in any of the above 50 arrangements may be inclined slightly upward beneath the container *B* to cause the door *D* to make a tight joint therewith.

As shown in Fig. 6 the fuel hopper or container *B* is constructed at the bottom with hinged doors *L* provided with 55 runners or rollers *l* which are normally held closed by a rail or rails *M* or a plate carried by the trolley *C* so arranged that when the carriage is withdrawn with the furnace 60 door *F* the doors *L* are allowed to drop and discharge the contents of the hopper *B* into the furnace. Or as shown in Fig. 7, the runners or rollers *l* may be carried by the carriage and engage rails, battens or the 65 like *M* on the doors *L* of the container.

As shown in Fig. 8 instead of using a fixed hopper or container *B* a removable hopper or skip *B'* may be employed having a bottom door *L* of the type last described adapted to be placed in position over the 70 furnace opening and so arranged that the doors *L* may be released or opened in the manner just described. The doors *L* of the skip as shown may be held closed by its own weight by means of the supporting chain or sling *N* by which it is hung or carried by a crane or the like and may be adapted to be freed so that they can open when the skip is lowered into position, and the weight is taken off the chain or sling. 75

In Fig. 9 the invention is shown applied to a movable container consisting of a number of separate compartments or receptacles *B* arranged in one truck or the like *O* adapted to be moved backward and forward 80 over the furnace opening *A* to bring each separate compartment *B* thereover. The bottom of each separate compartment *B* is constructed with one or more doors *L* as above described adapted to be released or 85 opened to discharge the contents into the fire. This may be accomplished in the manner above described, rails, battens or the like being employed to retain the doors of the compartments closed when they are not 90 over the furnace opening, or as shown the doors *L* of the separate compartments may be normally held closed by the rail or runway *P* over which the truck *O* travels, being 95 released at a gap or break *R* in the rail 100 which is arranged over the furnace opening. This gap is normally maintained closed by a short length of rail *p* held in position by the carriage *C*. In some cases the carriage *C* may be dispensed with the 105 guide to retain the rail *p* in position being carried directly by the carriage *E*.

What I claim as my invention and desire to protect by Letters Patent is:—

1. In a furnace closing and charging 110 means for refuse destructors and other furnaces, the combination of a furnace having a seal around its inlet opening, carriages co-operating with the inlet opening of the furnace, one carriage embodying a door for the 115 furnace and said door having rising and depressing movements relatively to the furnace inlet and provided with flanges to engage the seal, and the other carriage having a charging means for the furnace, one carriage being connected to and operated with the other, and means for operating the carriages. 120

2. In a furnace closing and charging 125 means for refuse destructors and other furnaces, the combination of a furnace having an upper inlet opening, rails at different elevations relatively to the inlet opening of the furnace, carriages mounted to move on the rails, one above the other, and associ- 130

ated for movement one by the other, one carriage embodying a rising and depress-door for the furnace inlet and the other a charging means for the furnace, said charging means being movable with its carriage, and means for operating the carriages.

3. In a furnace closing and charging means for refuse destructors and other furnaces, the combination of a furnace having an upper inlet opening, carriages arranged one above the other, the lower carriage embodying a rising and depressing closure for the furnace and the upper carriage having a charging means for the furnace, and means for operating the carriages.

4. In a furnace closing and charging means for refuse destructors and other furnaces, rails adjacent to the inlet of the furnace, structurally independent superposed carriages longitudinally shiftable on the rails, one carriage embodying a door for the furnace and the other having a charging means for the furnace, one carriage being connected to and operated with the other, and means for operating the carriages.

5. In a furnace closing and charging means for refuse destructors and other furnaces, the combination of a furnace having an upper inlet opening and a container for holding material for charging the furnace through said opening, rails at different ele-

vations, a carriage embodying a rising and depressing closure for the furnace and engaging the lower rails, the lower rails having depressions therein, a second carriage 35 having a closure for the container, the carriages being associated for movement of one by the other, and mechanism for operating both carriages.

6. In a furnace closing and charging 40 means for refuse destructors and other furnaces, the combination of a furnace having an upper inlet opening and a container for holding material for charging the furnace through the said opening, shiftable closing 45 means for the furnace having a rising and falling movement, shiftable closing means for the container operatively associated with the closing means for the furnace whereby the one closing means may be actuated by the other, and means for operating the closing means for the furnace and container whereby the closing means for the furnace is fully opened before the closing 50 means for the container commences to open. 55

In testimony whereof I have hereunto set my hand in presence of witnesses.

HENRY NORMAN LEASK.
